UNITED STATES PATENT OFFICE

GEORGE V. GAVAZA, OF QUINCY, MASSACHUSETTS

RECEPTACLE FILLING DEVICE

Application filed April 14, 1930. Serial No. 444,088.

The present invention relates to receptacle filling devices, and more particularly to combined filling and draining devices such, for instance, as are used to fill and drain the 5 tubs of household clothes-washing machines.

It has been proposed heretofore to provide households with devices for filling and draining the tubs of clothes-washing machines. These devices usually comprise a T 10 having a lateral outlet to which a long flexible conduit, for conducting water to the tub, is connected. The bottom of the T is provided with a second outlet to which a short flexible conduit is connected. The other end of the 15 short conduit is attachable to a hot water faucet. The top of the T is provided with a third outlet, having a constriction therein, to which a tube attachable to a cold water faucet is connected. When the tube and the short 20 conduit are connected, respectively, to the cold and hot water faucets the tub is filled with water which flows through the long conduit. When the short conduit is disconnected from the hot water faucet and the open end 25 of the conduit is positioned in the sink the cold water is restricted by the entrance to the third outlet of the T to a jet which flows swiftly past the lateral outlet to which the long conduit is connected and out of the open 30 end of the short conduit. The velocity of the jet in passing the lateral outlet tends to draw air out of the long conduit, thus to produce a condition of unbalanced pressure between the water in the tub and the open end of the short 35 conduit. This condition of unbalanced pressure causes the air on the surface of the water in the tub to push it up the long conduit and out of the open end of the short conduit into the sink. To start the siphon action it is 40 necessary to pinch or bend the short conduit for an instant. Many users of the device fail to pinch or bend the short conduit to start the siphon action and then complain that the device is defective.

The principal object of the present invention is to produce a combined filling and draining device in which the siphon action starts automatically.

To the accomplishment of this object and such others as may hereinafter appear, the

features of the present invention consist in certain devices, combinations and arrangements of parts fully described hereinafter and then pointed out in the claims which possess advantages readily apparent to those skilled in the art.

The various features of the present invention will be readily understood from an inspection of the accompanying drawing illustrating the best form of the invention at present known to the inventor, in which,

Figure 1 is a view in elevation showing in full and construction lines, respectively, the device in use to fill and drain a receptacle;

Fig. 2 is a detail view in sectional elevation of the T and the tube connected thereto;

Fig. 3 is a detail view in sectional elevation of the short flexible conduit, and

Fig. 4 is a view in perspective of the baffle.

In the illustrated embodiment of the invention the combined filling and draining device comprises a T 5 (Fig. 2) having three outlets 6, 7 and 8. Adjacent the outlet 6, the T 5 is shouldered to receive one end of a long flexible conduit 9 (Fig. 1) the other end of which extends into the receptacle or tub 10 to be filled and drained. The conduit 9 is clamped to the T 5 by a metallic ferrule 11. Adjacent the outlet 8 the T 5 is shouldered to receive one end of a short flexible conduit 12 the other end of which is provided with an integral roll 13 to permit the conduit 12 to fit over the smooth face of the hot water faucet 14 (Fig. 1). The conduit 13 is clamped to the T 5 by a metallic ferrule 15. The third outlet of the T 5 is threaded to receive a threaded nipple 16 which is secured to one end of a short rubber tube 17 by a metallic ferrule 18. The other end of the tube is provided with a rolled end 19. Adjacent its rolled end 19 the tube 17 is frusto-conical to enable it to be slipped tightly over the shoulder on the threaded end of a cold water faucet 20.

In order to make the end of the tube 17 frusto-conical, after the tube is extruded the open end thereof is expanded before vulcanization by means of a frusto-conical plug 21 which remains in place during the vulcanization of the tube. By means of its frusto-con-

ical end the tube 17 may be coupled to faucets varying widely in diameter. In many cases it may be desirable to use the device as a filler only. In such cases the tube 9 may be plugged or tied into a knot and either the rolled end 13 or the rolled end 19 may be coupled to the faucet 20, depending upon the size thereof. That is, if the faucet is large the rolled end 19 is coupled thereto. If the faucet 20 is 10 small the ends may be reversed and the rolled end 13 coupled to the faucet.

When used as a combined filler and drainer the device may be coupled to the cold water faucet 20 with the long conduit 9 positioned in 15 the receptacle 10 and the short conduit 12 rolled into engagement with the hot water faucet 14. The receptacle may thus be filled with water having the proper temperature. To drain the receptacle the short conduit 12 20 is detached from the hot water faucet and the free end of the conduit is positioned in the sink 22 (Fig. 1). The cold water is then turned on. Velocity is imparted to the cold water by the restricted entrance 23 in the T 5. 25 This restricted entrance converts the stream of cold water into a jet which travels centrally down through the T 5 and the conduit 12 leaving an annular space between the jet and the internal wall of the conduit. This 30 space allows air to enter the open end of the conduit and flow into the conduit 9 thus maintaining a condition of balanced pressure on the water in the tub 10 notwithstanding the tendency of the jet in passing the outlet 6 to 35 draw air from the conduit 9.

In order to prevent the atmospheric air from passing up the conduit 12 to the conduit 9 the conduit 12 is provided with a baffle 24. As shown in Figs. 3 and 4 the baffle 24 is a 40 hollow ferrule having on one end an inturned flange 25. With this construction the jet of water is free to flow centrally down the conduit 12, but the air entering the conduit 12 is prevented by the flange 25 from passing 45 beyond the baffle 24. Thus the jet of water in passing the outlet 6 is able to create a condition of unbalanced pressure between the water in the tub 10 and the open end of the conduit 12 to cause the expulsion of the water 50 therefrom into the sink 22 under the influence of atmospheric air acting upon the water in the tub 10.

Because of the baffle 24 the siphon action 55 will start as soon as the rolled end of the conduit 12 is uncoupled from the hot water faucet and positioned in the sink 22. Thus it is no longer necessary to pinch or bend the conduit 12 to initiate the siphon action.

What is claimed as new, is:

- 60 1. In a combined filler and drainer, a T having three outlets, two flexible conduits connected, respectively, to two of said outlets, a tube connected to the third outlet, a coupling for connecting the tube to a faucet, 65 the shorter one of said conduits having

integral means for connecting it to a faucet and means for preventing simultaneous flow of water and air therein in opposite directions when its open end is positioned for draining.

2. In a combined filler and drainer, a T having three outlets, one of which is restricted, a tube connected to the restricted outlet, two flexible conduits connected, respectively, to the other two outlets, a coupling for connecting the tube to a faucet, the shorter one of said conduits having a baffle insertable as a unit through its open end for preventing atmospheric air from entering the open end of the shorter conduit and flowing to the longer one of said conduits.

3. In a combined filler and drainer, a T having three outlets, one of which is restricted, a tube connected to the restricted outlet, two flexible conduits of different lengths connected, respectively, to the other two outlets, a coupling for connecting the tube to a faucet, the shorter one of said conduits having a hollow tube therein, said tube having an inturned flange on one open end thereof permitting water to pass through the tube and out of the open end of the short conduit while preventing air from passing up the short conduit into the long conduit.

In testimony whereof I have signed my name to this specification.

GEORGE V. GAVAZA.
